Primary Examiner — Llorellys Martinez*(74) Attorney, Agent, or Firm* — The Webb Law Firm(57) **CLAIM**

The ornamental design for a beveled berm, as shown and described.

DESCRIPTION

FIG. 1 is a top view of a beveled berm showing our new design; and,

FIG. 2 is a top, front, and left side perspective view thereof. The broken lines in the drawings represent portions of the beveled berm that form no part of the claimed design.

1 Claim, 2 Drawing Sheets(56)
